LETTERING AND MARKING GUIDE

Edmund W. Watkins, Palatka, Fla.

Original application May 27, 1938, Serial No. 210,515. Divided and this application October 19, 1938, Serial No. 235,845

10 Claims. (CL. 33—184.6)

This invention is a novel improvement in lettering guides for land markers and the like, the present application being a division of my co-pending application Serial No. 210,515, filed May 27, 1938; and one object of the invention is to provide a novel lettering guide for use in marking the metallic or other caps of land markers or the like, which markers usually comprise a metallic plate or cap bearing appropriate markings having a part permanently anchored in a concrete or other base so as to form an integral part thereof, the markers being primarily used as permanent reference monuments required by certain State map laws, also as permanent markers respecting township, section, town-lot corners, and as markers for corners of sub-divisions of United States surveys; also used as inexpensive and durable grave markers.

Another object is to provide a novel lettering guide for use in marking said metallic plates or caps, the use of which will speed up the establishment of permanent land markers, said guide comprising a light portable field-skit adapted to be mounted upon the cap and conveniently used for the lettering and marking thereof before or after the monuments have been established in the earth, the guide permitting a wide latitude or diversification in the designs of said markings and lettering upon the cap while at the same time serving to standardize the marking and lettering of boundary markers for corners or the like, same resulting in uniform spacing of letters and figures, and also serving as a convenient and practical means for conforming with certain State map laws respecting said permanent reference monuments.

I will explain the invention with reference to the accompanying drawings which illustrate several practical embodiments thereof to enable others to adopt and use the same; and will summarize in the claims the novel features of construction, and novel combinations of parts, for which protection is desired.

In said drawings:

Fig. 1 is a top plan view of a monument with a cap embedded therein, and bearing indicia impressed therein by means of my novel lettering guide.

Fig. 2 is a side elevation of the upper portion of the monument shown in Fig. 1.

Fig. 3 is a top plan view of an unmarked metal cap, detached.

Fig. 4 is a side elevation thereof.

Fig. 5 is a perspective view of the pointed pin.

Fig. 6 is a top plan view showing my novel

lettering guide for impressing the lettering and other indicia applied to the cap of the monument shown in Fig. 1.

Fig. 7 is a side elevation of the lettering guide applied to the monument shown in Fig. 6. 5

Figs. 8 and 9 are perspective views of lettering and numbering dies used in connection with the guide.

Fig. 10 is a perspective view of the die used in connection with the guide for impressing radial lines in the cap. 10

Figs. 11 to 16 inclusive show modifications in the designs in the markings which may be impressed in the cap, using the guide.

The land marker shown in Figs. 1-4 comprises 15 a metal cap 1, preferably of non-corrosive metal or material, and of substantial thickness, and of circular shape, said cap having an axially disposed tubular extension 1a on its underside, the bore 1b of said extension continuing upwardly 20 through the cap 1. Cap 1 is permanently mounted in a base 2, which may be of metal but is preferably a concrete block of any desired cross-section, said cap being so embedded therein that a portion thereof projects above the upper 25 face of base 2. A pin 3 is also provided for cap 1, said pin having a conical head and having a shank 3a (Fig. 5) adapted to be forcibly inserted down into bore 1b of the cap as indicated in Fig. 2 to close the said bore and to exclude dirt and 30 other foreign matters from the bore. 30

My novel lettering guide comprises a plate 4 (Figs. 6 and 7) preferably of circular shape having a central opening 4a adapted to receive the peripheral portion of cap 1, said plate having 35 diametrically disposed depending lugs 4b projecting from its underside adjacent the periphery provided with tapped bores for the threaded shanks of opposed thumb nuts 4c having shoes 4d adapted to engage the side walls of the base 2 40 as shown in Fig. 7 to securely clamp the plate 4, in the position shown, and prevent rotation of the plate on the base. In plate 4 adjacent the periphery is an annular series of evenly spaced holes 4e preferably disposed about 9° apart so 45 that there will be provided ten such holes for each quadrant, or a total of forty holes in the entire series. However, the number of holes 4e may be increased or decreased to vary the spacing, as desired.

Rotatably mounted upon plate 4 is a pointer 5 (Figs. 6-7) of substantial width and thickness, same having a central bore 5a in which a rod 5b is secured at its upper end by a pin 5c, rod 5b being adapted to be inserted down through open- 50

50

45

55

55

ing $1b$ of cap 1 and to snugly fit said bore, the rod serving as pivot whereby pointer 5 may be rotated with respect to plate 4 . Preferably the underside of the pointer 5 is recessed as at $5d$ (Fig. 7) so as to clear the upwardly projecting portion of cap 1 .

One end of pointer 5 terminates in a point $5e$ terminating adjacent the pitch circle of the series of holes $4e$ as indicated in Fig. 6, while the other end is extended as at $5f$ to form a handle whereby the pointer may be readily rotated on the plate 4 . Upon the top of handle $5f$ is a pivotally mounted thumb lever $5i$ having its inner end terminating above the pitch circle of the holes $4e$ and carrying a pin $5j$ which is slidably mounted in a bore in the handle $5f$, said pin being adapted to enter any of the holes $4e$ in plate 4 . Thumb lever $5i$ is normally tilted so as to engage pin $5j$ with a hole $5e$ by a spring $5k$ disposed between the opposite end of thumb lever $5i$ and the top of the handle $5f$, as shown in Fig. 7. By depressing the outer end of thumb lever the pin $5j$ will be raised out of engagement with the hole $4e$, and pointer 5 may be rotated into any desired position over any of the other holes, and upon releasing lever $5i$ the pin $5j$ will enter the underlying hole $4e$ and will lock the pointer 5 in said adjusted position.

Extending axially of pointer 5 is a narrow slot $5m$ disposed at each side of pin $5b$ and extending substantially the entire diameter of cap 1 . The slot $5m$ forms a guide for a thin die 7 (Fig. 10) of relatively great width adapted to form radial lines in cap 1 when the die in said slot $5m$ is struck by a hammer. The width of the die 7 is substantially equal to the length of the slot $5m$ at each side of pin $5b$. One end of slot $5m$ is enlarged as at $5n$ to form a rectangular guide for lettering and numbering dies 6 (Figs. 8 and 9) having rectangular shanks $6a$ of size to suit the enlargement $5n$. Preferably the dies 6 shown in Figs. 8 and 9 are custom made steel dies and may be inserted down through the opening $5n$ of the pointer and hit with a hammer to cut the letters or numbers in the cap. The opposite end of slot $5m$ is provided with a similar enlargement $5p$ forming a rectangular guide of same size as guide $5n$, however, one wall of slot $5m$ forms one wall of the guide $5p$, whereas the guide $5n$ is coaxial with the slot $5m$. Thus while the guides $5n$ and $5p$ are disposed on the same pitch circle, since the axis of guide $5p$ is offset from the axis of guide $5n$ a distance approximately equal to half the spacing of the holes $4e$ in plate 4 the lettering or figuring may be impressed on cap 1 at intervals of $4\frac{1}{2}^\circ$ or 9° apart according to the spacing of holes $4e$ shown in Fig. 7. A third enlargement $5q$ is also provided in slot $5m$ adjacent the guide $5p$, but is disposed nearer the pin $5b$, the enlargement $5q$ forming with the wall of slot $5m$ a guide of same size as guides $5n$ and $5p$. The dies such as shown in Figs. 8 and 9 may be used in connection with any of the guides $5n$, $5p$ or $5q$. By manipulating the pointer 5 , and by using the dies 6 and 7 , various designs of lettering, numbering and radial lining may be impressed in cap 1 using the guides $5m$, $5n$, $5p$ and $5q$, some of the designs being shown in Figs. 1 and 11-16 and any desired angle or course may be impressed thereon within a limit of $4\frac{1}{2}^\circ$.

In Fig. 1 three angle or course lines a are illustrated on the cap impressed by die 7 through guides $5m$; also the names of land owners, viz: "Walton" and "Browning" are im-

pressed in two sectors using dies 6 through guides $5n$, $5p$, or $5q$; and the notation "66 Ft. Highway" impressed in a similar manner within the other sector. In Fig. 11 radial lines a denoting 0° , 45° , 90° , 130° , 270° , and 351° are impressed. In Fig. 12 a different arrangement of three radial lines a is illustrated, with notations "Barnett", "13th St." and "A. C. L. R. R. Co." impressed in the respective sectors. Fig. 13 illustrates the cap used as a grave marker; the radial lines being omitted; Fig. 14 illustrates a marking for townlot corners, using radial lines a , and appropriate indicia impressed within the sectors; Figs. 15 and 16 illustrate section, township, corner, or quarter-section corner markings.

After the cap 1 has been given the desired markings, plate 4 and pointer 5 are removed, and the pointed pin 3 is then forcibly inserted down into bore $1b$ of the cap to exclude dirt and other foreign matter from the bore, the pin being preferably retained in the bore by friction.

The guides $4-5$ provide means for standardizing marking and lettering of boundary markers for land and lot corners, and permit of a wide latitude and diversification in making such designs as shown in Figs. 1 and 11-16. Obviously many other designs could be made. The use of my guide provides a practical way of complying with certain State map laws which require permanent reference monuments. The cap plate may be marked using the lettering guide either before or after the cap has been mounted in the base, and its use permits great speed in establishing permanent reference land markers, and provides a long-felt want for marking permanent township, section, also other corners of sub-divisions of the United States surveys, also town-lot corners; and the marking may be applied in a symmetrical manner with uniform spacing of letters and figures.

I do not limit my invention to the exact form shown in the drawings, for obviously changes may be made therein within the scope of the claims.

I claim:

1. A lettering guide for land markers or the like having an indicia receiving cap mounted in a face of a supporting base and having an axial bore; said guide comprising a plate having its central portion removed in way of the cap; means for mounting the plate on the base; a rotatable member on the plate having a pivot engaging the bore of the cap; said member having die receiving guide openings therein disposed over the plate; and means for locking the member in position on the plate.

2. In a guide as set forth in claim 1, said locking means comprising an annular series of spaced holes in the plate adjacent the periphery thereof; said member having a handle portion extending beyond the pitch circle of the holes, a pin slidably mounted in a bore in said member and adapted to engage any of said holes; and means on the handle portion for normally urging the pin into engagement with a hole.

3. In a guide as set forth in claim 1, said locking means comprising an annular series of spaced holes in the plate adjacent the periphery thereof; said member having a handle portion extending beyond the pitch circle of the holes, a pin slidably mounted in a bore in said member and adapted to engage any of said holes; a thumb lever pivoted on said handle portion and having one end connected with said pin; and spring means cooperating with the other end of the lever

normally tilting the lever to urge the pin into engagement with the hole.

4. In a guide as set forth in claim 1, said guides comprising rectangular openings in the member disposed different distances from the pivot and adapted to receive correspondingly shaped lettering and numbering dies.

5. In a guide as set forth in claim 1, said guides comprising rectangular openings in the member disposed different distances from the pivot and adapted to receive correspondingly shaped lettering and numbering dies, the axes of the openings being offset laterally from the axis of the member.

15 6. In a guide as set forth in claim 1, said guide openings comprising narrow coaxial slots in the member at each side of the pivot, each embracing the radius of the cap and adapted to receive correspondingly shaped dies for impressing radial lines in the cap, said slots having rectangular enlargements adapted to receive correspondingly shaped lettering and numbering dies.

7. In a guide as set forth in claim 1, said guide openings comprising narrow coaxial slots in the member at each side of the pivot, each embracing the radius of the cap and adapted to receive correspondingly shaped dies for impressing radial lines in the cap; said slots having rectangular enlargements adapted to receive correspondingly shaped lettering and numbering dies, some of the enlargements being disposed at different distances from the pivot than others.

25 8. In a guide as set forth in claim 1, said guide openings comprising narrow coaxial slots in the

member at each side of the pivot each embracing the radius of the plate and adapted to receive correspondingly shaped dies for impressing radial lines in the cap, said slots having rectangular enlargements adapted to receive correspondingly shaped lettering and numbering dies, some of the enlargements being disposed at different distances from the pivot than others, and some of the enlargements being offset laterally from the axis of the member.

10 9. A lettering guide for land markers having an indicia bearing cap projecting beyond a face of a supporting base and having an axial bore; said guide comprising a plate having a central opening receiving the projecting portion of the cap; means for mounting the plate on the base; a rotatable member on the plate having a pivot engaging the bore of the cap; said member having die receiving guide openings therein disposed over the plate; and means for locking the member in position on the plate.

15 10. In a guide as set forth in claim 9, said guide openings comprising narrow coaxial slots in the member at each side of the pivot, each embracing the radius of the plate and adapted to receive correspondingly shaped dies for impressing radial lines in the cap, said slots having rectangular enlargements adapted to receive correspondingly shaped lettering and numbering dies, some of the enlargements being disposed at different distances from the pivot than others, and some of the enlargements being offset laterally from the axis of the member.

EDMUND W. WATKINS.
